CLAIM

The ornamental design for pendant, as shown and described.

DESCRIPTION

FIG. 1 is a front view of a pendant showing my design, the broken line illustrating the environment in which the pendant may be used and forming no part of the claimed design, the environment being a generic necklace from which the pendant can hang;

FIG. 2 is a left-side view thereof;

FIG. 3 is a rear view thereof;

FIG. 4 is a perspective view thereof;

FIG. 5 is a top view thereof;

FIG. 6 is a bottom view thereof; and,

FIG. 7 is a right-side view thereof.
